JOHN KINGSBURY.

UNITED STATES PATENT OFFICE.

JOHN KINGSBURY, OF ALBANY, NEW YORK.

DESIGN FOR A LANDAU-SLEIGH.

SPECIFICATION forming part of Design No. 17,874, dated November 8, 1887.

Application filed October 3, 1887. Serial No. 251,385. Term of patent 7 years.

To all whom it may concern:

Be it known that I, JOHN KINGSBURY, of the city and county of Albany, in the State of New York, have invented and produced a new and original Design for a Landau-Sleigh, of which the following is a full and exact description, reference being had to the accompanying photographic illustration, which forms part of this specification, and which shows a side perspective view of my new landau-sleigh.

Heretofore the bodies of landau-sleighs have generally had their quarter-panels, belts, and cheek-pieces carried in a continuous unbroken line from the rear end of the body to the foot-board under the driver's seat. The only exception to this rule that I am aware of is shown and described in the Design Patent No. 17,631, granted to me August 16, 1887, wherein these bodies have seemingly been divided into two distinctive parts, with the after part or main body of greater width than the forward extension; but therein the rocker which forms the sunken bottom of the main body terminated at the forward end of the main body, at which point said main body had the form of a coupé-pillar.

The leading features of my present design consist in the body of the sleigh, which presents the appearance of two distinctive parts, the after part or main body having a greater width than the forward extension, the line of demarcation being a convex sweep, and the forward extension being a continuation of the "rocker" or sunken bottom of the main body; and it also consists in the rearward terminal of the ornamental scroll that is interposed between the body of the sleigh and runners, the same being a curvature—that is, a continuation of the curve of the rearmost end of the runners.

As represented in the accompanying photographic illustration, A designates the runners of the sleigh, which at their forward part are bent upwardly on a curve, and then carried in an approximately-vertical line to their upper ends, which terminate in an ornamental head, 1. The rearmost ends of said runners have a convex outline, 2, which curves upwardly.

B designates the after part or main body of my landau-sleigh, whose sides, both in outline and

ornamentation, are substantially alike at both ends, and have the outward swell commonly given to sleigh-bodies. Both ends of the sides of said main body, beginning at the upper edge, have slightly-curved convex outlines 3, which at the points 4 join to quicker convex outlines 5, which, in their turn, merge into and join a flatter convex outline, 6, that defines the lower edge of the sides of said main body. The lower quarter-panel, C, is bordered on its lower side by a ravel-molding, 7, which is of a uniform width and follows the contour of the lower edge of the side of the main body as defined by the convex outlines 5 and 6. Both ends of said lower quarter-panel are pointed and substantially alike, and its upper edge is defined by a concave line, 8, which is formed by the lower edge of the belt D, which line joins the ravel-molding 7 at each end of the main body. The belt D extends from the rearmost to the foremost edge of the side of the main body, and its upper outline is formed by a concave line, 9, or compass-sweep, with which the lower line of said belt is parallel. The upper quarter-panels, E, of which there are two of substantially the same form, and the intermediate door-panel, E', have their lower outline defined by the upper edge of the belt D, and the upper outline of said upper quarter-panel is defined by an approximately straight horizontal line, 10, which extends across the side of the main body.

The door F has near its upper end a crest-panel or monogram-panel, 11, which is preferably of a rectangular form.

The forward extension, G, which includes the rocker H, begins under the after part of the main body B with a concave outline, 12, which sweeps downward and forward from the convex outline 5 at the rear end of the main body. The concave line 12 forms an angle, 13, with the lower convex outline, 14, which extends forward and runs nearly parallel with the convex outline 6 at the lower edge of the side of the main body B. At a point just forward of the door F the convex line 14 joins and is merged into an ogee outline, 15, that joins a horizontal outline, 16, under the "dickey-seat." The last-named line joins to an upwardly-inclined line, 17, which forms the outline of the lower edge of the bracket or foot-board I.

Beginning at the forward end of the main

body B, the forward extension, G, which is integral with but narrower than the said main body, has the following-named upper outline: The concave outline 18, which is bordered by 5 a parallel molding, 19, sweeps upwardly to join a horizontal line, 20, on which the dickey or driver's seat J is located. Sweeping downwardly and forward at the front of the latter is a concave outline, 21, which joins an upwardly-inclined straight line, 22, that forms the upper edge of the bracket I. The paneled dash-board K is at the forward end of the bracket I; but as said dash-board is fully described in my prior Design patent hereinbefore referred to, a further description is deemed unnecessary.

The ornamental scroll L, which is interposed between the under part of the body and the runners of my sleigh, does not materially differ from the one described in my prior Design patent, as above referred to, excepting in respect to the rearward terminal, 23, which in this design forms a continuation of the convex line 2 at the rearward end of the runners A.

25 What I claim as new, and desire to secure by Letters Patent, is—

1. In a design for a landau-sleigh herein described and shown, the shape and configuration of the main body B and forward extension, G, the first being defined by the convex lines 3, 5, and 6 and horizontal line 10, and the other being defined by the concave lines

12, 18, and 21, convex line 14, ogee line 15, horizontal lines 16 and 20, inclined lines 17 and 22, and dickey-seat J, as herein specified. 35

2. In a design for a landau-sleigh herein described and shown, the ornamentation of the sides of the main body B, consisting of the lower quarter panel, C, whose opposite ends have substantially the same form, as defined by the upper edge of the ravel-molding 7 and the concave line 8, formed by the lower edge of the belt D, the parallel belt D, as defined by the concave outline 9, the upper edge of the lower quarter panel, and the convex end lines, 40 3, and the upper quarter panels, E, and door-panel E', as defined by the upper line, 9, of the belt D, convex end lines, 3, and horizontal line 10, as herein specified. 45

3. In a design for a landau-sleigh herein described and shown, the shape and configuration of the forward extension, G, and rocker H, whose upper outline is defined by the curved lines at the lower edge of the main body B, concave outlines 18 and 21, horizontal 50 line 20, and inclined line 22, and whose lower outline is defined by the concave line 12, convex line 14, ogee line 15, horizontal line 16, and inclined line 17, as herein specified. 55

JOHN KINGSBURY.
